(57) **CLAIM**

The ornamental design for a chopper chariot trailer, as shown and described.

DESCRIPTION

FIG. 1 is a rear perspective view of a chopper chariot trailer. FIG. 2 is a front elevational view of the chopper chariot trailer.

FIG. 3 is a rear elevational view of the chopper chariot trailer.

FIG. 4 is a right side elevational view of the chopper chariot trailer, the left side elevational view being a mirror image thereof and, accordingly, not shown.

FIG. 5 is a top plan view of the chopper chariot trailer; and, FIG. 6 is a bottom plan view of the chopper chariot trailer.
